UNITED STATES PATENT OFFICE

ALBERT WIDMAN, OF NEWCASTLE, INDIANA

VALVE SILENCER

Application filed May 23, 1928. Serial No. 279,991.

The present invention relates to improvements in valve silencers, and has reference more particularly to means applicable to the valve actuating mechanism of an internal combustion engine for eliminating the clicking noises that are incidental to the valve operation:

One of the important objects of the present invention is to provide a valve silencer that can be readily and easily positioned on the end of a valve stem for cooperation with the valve tappet cam, means being provided for maintaining the silencer in engagement with the cam or tappet.

15 A further object is to provide a valve silencer which includes a non-metallic impact member for disposition between the valve stem and its tappet.

Still a further object is to provide a valve silencer of the above mentioned character which is simple in construction, inexpensive, strong and durable and further well adapted to the purpose for which it is designed.

Other objects and advantages of the invention will become apparent from the following description when taken in connection with the accompanying drawing.

In the accompanying drawing wherein like reference characters indicate like parts 30 throughout the several views:

Figure 1 is a side elevation of the valve silencer embodying my invention, showing the same associated with the tappet of a rocker arm employed with an engine having overhead valves, and showing the manner in which the silencer is positioned on the upper end of the valve stem.

Figure 2 is a similar view showing the silencer positioned on the lower end of a valve stem and in engagement with a tappet that is associated with an engine of a different type.

Figure 3 is a vertical sectional view through the valve silencer per se.

Figure 4 is a bottom plan view thereof, and

45 Figure 5 is a detail perspective view of the non-metallic impact member.

In the drawing wherein for the purpose of illustration is shown the preferred embodiment of my invention, the numeral 1 designates generally my improved valve silencer,

the same comprising a metallic sleeve 2 that is formed at one end with a relatively thick annular flange 3 on its outer face and as is clearly disclosed in Figure 3, the outer face of this flange is rounded. The outer end of the sleeve 2 is formed in its bore with the annular beveled retaining lip 4, the purpose of which will be presently described.

The other end of the sleeve has its inner and outer walls beveled as illustrated at 5 and 6, respectively, and this feature is also clearly illustrated in Figure 3.

Initially the sleeve 2 is formed of soft steel and after the lip 4 has been formed, the structure is case-hardened.

Also forming a salient part of the present invention is the non-metallic impact member 7 shown in Figure 5, and this impact member may be constructed of a suitable composition including fiber or the like. The impact member is in the form of a circular plug which is of a diameter slightly greater than the diameter of the bore of the sleeve and is adapted to be pressed through the bore, the beveled inner end 5 providing a means for guiding the impact plug into the bore of the sleeve, the outer edge portion of this non-metallic plug 7 is beveled as at 8 for cooperation with the beveled lip 4, and furthermore the outer face of this plug is rounded to provide a convex tappet engaging surface 9. As is clearly shown in Figure 3, the convex surface 9 of this impact plug 7 when in proper position in the outer end of the sleeve forms a continuation of the curved outer face of the flange 3.

In Figure 1 wherein the valve silencer is shown as being used in conjunction with the tappet 10 associated with one end of the rocker arm 11 of an engine of the overhead valve type. The sleeve 2 is slidably fitted on the upper end of the valve stem 12. The usual valve spring associated with the valve stem is shown at 13, and the cap 14 is secured on the valve stem for engagement with the upper end of the valve spring 13 in the conventional manner. A washer 15 is disposed on the upper end portion of the valve stem 12 for rest on the cap 14, and a relatively light coil spring 16 encircles this upper end por-

tion of the valve stem and the sleeve 2 of the valve silencer 1. The lower end of the coil spring 16 engages with the washer 15, while the upper end engages with the bottom face 5 of the flange 3 for the purpose of normally urging the convex surface 9 of the non-metallic impact member 7 upwardly and in engagement with the tappet 10.

In Figure 2, the valve silencer is shown as 10 being associated with a different type of valve actuating mechanism wherein the lower end of the valve stem 17 has ordinary engagement with the tappet 18, which tappet is vertically slidable through suitable guide means 15 (not shown) at a point above the usual cam shaft and the cam engages with the lower end of this tappet 18 in the manner also well known in the art.

A relatively light coil spring 19 encircles 20 the lower end portion of the valve stem 17 on which is slidably fitted the valve silencer 1, the lower end of the spring engaging with the flange 3, while the other end of said spring engages with a washer 20 that is arranged 25 on the valve stem for disposition against the bottom of the valve spring cap 21, the valve spring being shown at 22.

It will thus be seen from the foregoing description that I have provided a valve 30 silencer for association with the valve actuating mechanism of an engine of an automobile for eliminating the clicking noises that as a rule are incidental to the valve operation. Furthermore, the valve silencer 35 will prevent the wear of the end of the valve stem that has normal engagement with the tappet, thus prolonging the life of the valve stem. Also, the use of a valve silencer of the above mentioned character will tend to 40 increase the efficiency of the operation of the engine as the valves will be caused to seat properly, thereby resulting in a reduction of the fuel consumption necessary to operate the engine.

45 The simplicity of my device enables the same to be constructed at a very low cost and by employing a non-metallic impact member, the same may be used for an indefinite time without necessitating replacement.

50 While I have shown the preferred embodiment of my invention, it is to be understood that minor changes in the size, shape and arrangement of parts may be resorted to without departing from the spirit of the invention and the scope of the appended claim.

Having thus described the invention, what I claim as new is:—

55 A valve silencer of the character described comprising a sleeve having a bore of uniform 60 diameter throughout adapted to be mounted on a valve rod, a beveled annular retaining flange on one end of the sleeve extending into the bore, a rounded head on one end portion of the sleeve providing an annular 65 shoulder on said sleeve intermediate its ends,

the outer surfaces of the head and flange being concentrically curved, a compressible plug having a convex upper end concentric with the flange and head and an inwardly beveled portion adjacent said upper end for engagement with the flange, detachably mounted in the bore and having its beveled portion engaged with the flange and its side wall frictionally engaging the wall of the bore, an expansible spring encircling the sleeve having one end supported on the valve rod and its opposite end impinged against the shoulder for urging the sleeve longitudinally on said rod.

In testimony whereof I affix my signature. 80
ALBERT WIDMAN.
